F. A. Balch;

Clothes Frame,

No 66,442.

Patented July 9, 1867.

United States Patent Office.

F. A. BALCH, OF HINGHAM, WISCONSIN.

Letters Patent No. 66,442, dated July 9, 1867.

IMPROVED CLOTHES OR TOWEL-RACK.

The Schedule referred to in these Letters Patent and making part of the same.

TO ALL WHOM IT MAY CONCERN:

Be it known that I, F. A. BALCH, of Hingham, in the county of Sheboygan, and State of Wisconsin, have invented a new and useful Improvement in Clothes or Towel-Racks; and I do hereby declare the following to be a full, clear, and exact description of the same, reference being had to the accompanying drawings, in which—

Figure 1 is a perspective view of my invention.

Figure 2 is a vertical longitudinal sectional elevation of the same.

Figure 3 is a plan of the same.

My invention consists in constructing folding clothes-bars with independent and permanent supports, by means of which the strain of supporting any article suspended from one of said bars may be transferred from the pivot-pin or bolt upon which they all move to a solid and permanent guide or ledge which will support the bar equally well in whatever position it may be placed.

That others may understand my invention, I will particularly describe it.

A A are the several bars, upon which articles of clothing or otherwise are to be placed for the purpose of drying them. B is the metallic head or frame by which the bars A are suspended from a wall or other convenient surface. Projecting from the frame B are the two plates C D, parallel with each other and at right angles to the frame B. The plates C D are located at a proper distance asunder to receive between them the thickness of the desired number of bars A, which in an ordinary or average-sized implement may number six or eight. Through the plates C and D holes are made to receive the upper and lower ends of the pivot-bolt E, which is provided with a head at one end and a screw-nut or its equivalent at the other, so as to retain it in its proper place. Between the plates C and D, and with regular intervals between them, are the curved ledges G G G, in number less by one than the number of bars. These ledges G are rigidly secured to the frame B, and they admit between them the ends of the bars, as shown in fig. 2, and they are of such extent or shape that the said ends will at all times be between them.

The operation of my clothes-rack is as follows: The frame B is attached to the wall by screws through the holes 3, which may be so shaped as to permit the frame to be detached from them by raising it bodily a little distance, when the screw-heads will come opposite a portion of the hole enlarged sufficiently to permit them to pass through. When not in use the bars are all turned back against the wall, and in that position occupy so little space that they form no obstruction in the room. When desired one or more of them may be drawn out so as to permit articles to be suspended upon them, and whichever one is so drawn out, or to whatever distance it is drawn out, it will receive the same support from the ledge G behind it, and in this particular it is entirely unlike any other clothes-bars which operate in a similar manner so far as I know. It will be advantageous to place metallic washers between the bars around the pivot, and metallic plates or friction-rollers on the ends of the bars where they rest against the ledges G.

Having described my invention, what I claim as new, and desire to secure by Letters Patent, is—

Constructing a folding clothes-rack with bars moving horizontally on a single pivot, with the ledges G behind said pivot, which will support said bars in a horizontal position equally well, whether partially or wholly extended, as set forth and described.

In combination with the folding bars A, frame B, plates C D, and pivot E, the ledges G G, as set forth and described.

F. A. BALCH.
